PHOTOCOPY EXPOSURE UNIT

Chester J. Abend, Camillus, and Karl E. Kober, Syracuse,
N.Y., assignors to SCM Corporation, a corporation of
New York

Filed Dec. 26, 1962, Ser. No. 72,966

Term of Patent 14 years

(Cl. D61—1)

Fig. 3

Fig. 4

Fig. 5

FIG. 6

FIG. 7

FIG. 8

FIGURE 1 is a front perspective view of a photocopy exposure unit showing our new design;

FIGURE 2 is another front perspective view with the cover in elevated position;

FIGURE 3 is a top plan view, to an enlarged scale, of the photocopy exposure unit shown in FIGURE 1;

FIGURE 4 is a right side elevation view, to an enlarged scale thereof;

FIGURE 5 is a left side elevation view, to an enlarged scale thereof;

FIGURE 6 is a front elevation view, to an enlarged scale thereof;

FIGURE 7 is a rear elevation view, to an enlarged scale thereof;

FIGURE 8 is a bottom plan view, to an enlarged scale thereof.

We claim:

The ornamental design for a photocopy exposure unit, substantially as shown.
